(57) **CLAIM**

The ornamental design for an electronic wristwatch, as shown and described.

DESCRIPTION

The application file contains at least one drawing executed in color. Copies of this patent application with color drawing(s) will be provided by the Office upon request and payment of the necessary fee.

FIG. 1 is a left front perspective view of an electronic wristwatch showing our new design;

FIG. 2 is a right front perspective view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a top plan view thereof;

FIG. 8 is a left front perspective view of a second embodiment of our design of FIG. 1, having red buttons, one on either side of the electronic wristwatch;

FIG. 9 is a right front perspective view of the second embodiment of the electronic wristwatch of FIG. 8;

FIG. 10 is a front elevational view of the second embodiment of the electronic wristwatch of FIG. 8;

FIG. 11 is a right side elevational view of the second embodiment of the electronic wristwatch of FIG. 8;

FIG. 12 is a rear elevational view of the second embodiment of the electronic wristwatch of FIG. 8;

FIG. 13 is a bottom plan view of the second embodiment of the electronic wristwatch of FIG. 8; and,

FIG. 14 is a top plan view of the second embodiment of the electronic wristwatch of FIG. 8.

The structural features depicted by broken lines shown in the drawings have been shown for the purpose of illustrating portions of the electronic wristwatch and do not form part of the claimed design.

For any color drawings, only the components shown in red are limited by color and all remaining components are not limited by color.
